UNITED STATES PATENT OFFICE.

JOSEPH ARONOFF, OF MONTREAL, QUEBEC, CANADA.

GARMENT POCKET.

Application filed May 10, 1920. Serial No. 380,315.

To all whom it may concern:

Be it known that I, JOSEPH ARONOFF, residing at 838 St. Lawrence Boulevard, in the city and district of Montreal, in the 5 Province of Quebec, in the Dominion of Canada, have invented new and useful Garment Pockets, of which the following is the specification.

The invention relates to garment pockets, 10 as described in the present specification and illustrated in the accompanying drawings that form part of the same.

The invention consists essentially in the 15 novel make of the pocket whereby the interior of the pocket may be reached without disturbing the safety portions in which valuables such as money and papers may be regularly kept.

The objects of the invention are to avoid 20 the felonious rifling of pockets by criminals in crowded vehicles and places; to devise a pocket for the purposes aforesaid that is simple and cheap to make, and at the same time very efficient; and generally to provide 25 a pocket which may be sold universally at a comparatively cheap price and without respect to the particular cut of the garment and yet retain its features of security that it is primarily designed for.

30 In the drawings, Figure 1 is a perspective view of a pair of trousers showing them cut away to disclose a side pocket.

Figure 2 is a fragmentary view showing 35 the arrangement of the pocket before being applied.

Fig. 3 is a perspective detail showing one side of the pocket illustrated in Figures 1 and 2.

Like numerals of reference indicate 40 corresponding parts in the various figures.

Referring to the drawings, the pocket 1, made for a pair of trousers, is fashioned after the style shown in Figures 1, 2 and 3, and constitutes a type of pocket that will 45 give really three pockets in one, and two of these pockets will be security pockets.

The piece of cotton or other material indicated by the numeral 1 is a perfectly plain piece of goods, and forms the pocket but toward the lower end it is caught up into 50 the fold 2 and an inner facing 3 is cut the same shape as the lower end of the piece of cotton 1 and extends upwardly in the fold as far as it will go. The fold is then stitched down the side as indicated by the dotted 55 line 4 and across the bottom and up the centre as indicated by the dotted line 5. The stitching 6 also extends across the top of the fold; but it does not include the inner facing 3. Other cross-stitching 7 is made 60 on the lower end of the fold, but does not include the inner facing 3, therefore the inner facing is quite free from the piece of cotton 1 except at the sides and in the middle, consequently by inserting the fingers 65 in the fold the pocket made between the fold and the piece 1 cannot be reached feloniously.

A further security is provided in the button 8 secured to the inner facing 3 and fastening to the fold 2 through the button-hole 9.

The piece 1 is folded on the line 10 and stitched at the edges of both sides and bottom, therefore there is a main pocket between the security pockets and the latter are protected in the folds 2.

What I claim is:—

In a garment pocket, side walls having a transverse fold and stitching along the 80 upper edge of said fold an inner facing covering the side walls below the fold and extending upwardly under said fold and having bottom, side and middle stitching, the latter extending upwardly and suitable 85 fasteners for detachably securing the inner facing under said fold.

Signed at the city of Montreal, Quebec, Canada, this 6th day of May, 1920.

JOSEPH ARONOFF.
